FOREIGN PATENT DOCUMENTS3525334 1/1987 European Pat. Off. .
2244029 11/1991 United Kingdom .*Primary Examiner*—Kay H. Chin
Attorney, Agent, or Firm—Seed and Berry[57] **CLAIM**

The ornamental design for a baby stroller upper frame and seat, as shown and described.

DESCRIPTION

FIG. 1 is a front perspective view of a baby stroller upper frame and seat showing my new design. The broken lines are for illustrative purposes only and form no part of the claimed design;

FIG. 2 is a left side elevational view thereof, the right side being identical;

FIG. 3 is a front elevational view thereof;

FIG. 4 is a rear elevational view thereof; and,

FIG. 5 is a bottom plan view thereof.
